Primary Examiner — Ricky Pham*(74) Attorney, Agent, or Firm* — Pearne & Gordon LLP(57) **CLAIM**

The ornamental design for a measuring cup for a mixer, as shown and described.

DESCRIPTION

FIG. 1 is an isometric view of a measuring cup for a mixer according to my new invention;

FIG. 2 is a top plan view thereof;

FIG. 3 is an enlarged front view thereof;

FIG. 4 is an enlarged rear view thereof;

FIG. 5 is a left view thereof;

FIG. 6 is a right view thereof; and,

FIG. 7 is an enlarged bottom plan view thereof.
